(57) **CLAIM**

The ornamental design for a table lamp, as shown and described.

DESCRIPTION

FIG. 1 is a left, front, and top perspective view of a table lamp, showing my design.

FIG. 2 is a right, rear, and bottom perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof.

FIG. 9 is a perspective view of the table lamp of FIG. 1 wherein a rotation shaft of the table lamp is elongated.

FIG. 10 is an elevation view of the table lamp of FIG. 5 wherein a rotation shaft of the table lamp is elongated; and,

FIG. 11 is an elevation view of the table lamp of FIG. 5 wherein a rotation shaft of the table lamp is elongated and the top of the table lamp is swiveling.

The broken lines shown in the drawings are included for the purpose of illustrating portions of the table lamp that form no part of the claimed design.

1 Claim, 11 Drawing Sheets
